[57] CLAIM

The ornamental design for a cosmetics applicator, substantially as shown and described.

DESCRIPTION

FIG. 1 is a rear elevational view of a cosmetics applicator, with its cover member in place, showing my new design;

FIG. 2 is a left side elevational view thereof;

FIG. 3 is a front elevational view thereof;

FIG. 4 is a right side elevational view thereof;

FIG. 5 is a bottom view thereof;

FIG. 6 is a top view thereof;

FIG. 7 is a partially exploded view showing the cover removed and partially shown in section, and showing the upper portion of the uncovered main portion exposing the applicator top, in a fragmentary left side elevational view, the lower portion being broken off;

FIG. 8 is a fragmentary front elevational view of the upper portion of the uncovered main portion; and

FIG. 9 is an enlarged top plan view of the uncovered main portion.

FIG. 1
